UNITED STATES PATENT OFFICE.

HARRY H. HANCOCK, OF SWAMPSCOTT, MASSACHUSETTS.

EXTENSION FURNITURE FOR PRINTERS.

1,397,486.

Specification of Letters Patent. Patented Nov. 15, 1921.

Application filed April 7, 1921. Serial No. 459,344.

To all whom it may concern:

Be it known that I, HARRY H. HANCOCK, a citizen of the United States, residing at Swampscott, in the county of Essex and State of Massachusetts, have invented certain new and useful Improvements in Extension Furniture for Printers, of which the following is a specification.

This invention relates to extension or adjustable furniture for the use of printers in locking up type within the chase; and one of the objects of the invention is to provide such furniture with two counterpart members, which are connected together to form a unitary article of manufacture, so that they may be longitudinally extended for substantially the entire length of the furniture, but without danger of separating the members, and so that there can be no relative transverse movement of the members. Another object of the invention is to provide simple, durable, efficient and practical extension or adjustable furniture for printers.

Prior Patent, #1,126,910, dated February 2, 1915, and granted to Henry E. Streetbig for self-adjustable marginal furniture for printers, is a type of printers' furniture over which the present invention embodies certain improvements. In the said patented device, the two members of the furniture may not only be moved transversely of each other, but they can be separated longitudinally. In other words, the said device comprises two members which can be separated entirely from each other, no matter what the adjusted length of the furniture may be, that is, whether the furniture is entirely collapsed, or is extended. One of the objects of the invention, therefore, is to present advantages which the said patented device does not.

The specified objects of the invention being some of those in view, the invention consists of certain features of construction and combinations of parts, to be hereinafter described, and then claimed, with reference to the accompanying drawings showing one embodiment of the invention, in which:—

Figure 1 is a perspective view of the improved printers' furniture, showing the members thereof collapsed or distended;

Fig. 2 is a perspective view, showing the members partially extended or adjusted;

Fig. 3 is a perspective view of one of the members detached from the other;

Fig. 4 is a plan of one face of the furniture, preferably the under-face, partly broken away; and

Fig. 5 is a transverse section on the line V—V, Fig. 2.

The improved article of furniture as shown in Fig. 1 is entirely collapsed, and when collapsed it may represent the normal condition of any of the twenty-four sizes of printers' furniture which may be employed under the present invention for locking up type, etc., in a printer's chase in place of the hundreds of sizes of ordinary furniture now in use. Of course, the number in a set of my improved furniture may be varied. The different sizes of furniture, under the present invention, have specific dimensions, except that the longitudinal dimension need not be specific. The vertical distance between the parallel upper and lower surfaces of the furniture shown in Fig. 1, in the extreme, is less than type-high, as otherwise various objections would be encountered in printing. The transverse dimension between the parallel, opposite, vertical side walls of the furniture is in any of the units of type measurement employed by printers. The unit may be of a pica measurement or nonpareil, or the measurement may be in fractions of an inch, so that the widths of the different sizes of furniture may be expressed as so many picas or fractions thereof, depending upon the size of the furniture. The furniture shown in Fig. 1 may be assumed to have a width of ten picas, a length of fifty-eight picas when entirely collapsed, and a length of eighty-six picas when fully extended, as these dimensions would be proper for one size.

Referring to the drawings, except Fig. 3, there are two members 10 and 11, and the construction and shape of these members is such that they are counterparts of each other, so that it is only necessary to duplicate one of the members in order to have two members for the complete article of furniture. These members are preferably composed of metal, such as an alloy mainly containing

aluminum, as for instance, an alloy of aluminum and copper, or the alloy may be of zinc and copper, and in fact, any suitable metal or alloy, or even suitable wood, etc.

- 5 The member 10 comprises in the main a larger body portion provided with a longitudinal tongue 12, which is shown as of the same length as the body portion of said member. The member 11 also comprises a 10 larger body portion provided with a tongue 13 similar to the tongue 12. The larger body of each member has opposite upper and lower walls 14, 15, extending in parallel planes, and the said walls receive between them, within a deep longitudinal recess 16, the corresponding tongue 12 or 13, as the case may be.

In practice, each member, such as shown in Fig. 3, is preferably composed of one 20 piece of metal so that an integral half of the furniture is provided; or, if desired, the tongue of the member may be formed as an extension of a strip which is placed between two opposite side pieces of metal, the three 25 parts being spot-welded, and the form being substantially as shown in Fig. 3. Of course, the said members may be otherwise constructed. It is preferred to make each of the members, such as shown in Fig. 3, by the die- 30 casting process.

If two members, such as shown in Fig. 3, are placed together to produce an article of furniture as shown in Fig. 1, the proportions and arrangement of the parts and 35 surfaces thereof will be as follows: There will be a plane of separation between the members 10, 11, at 17, which plane of separation extends longitudinally of the furniture and is formed by the vertical wall of the 40 recess 16 of each member, the vertical inner wall of the tongue, extended in alinement from each member, and between the contacting surfaces of said walls with the adjacent walls of the other member. Preferably, the 45 height of these walls is approximately half of the height of the furniture, and as the recess 16 in each member is rectangular, the tongue which fits therein is also made rectangular, transversely. The entire article of 50 furniture is rectangular in cross section, and the plane of separation 17 is preferably midway between the opposite vertical or outer walls of the completed article of furniture and is parallel therewith. By making the 55 tongue of each member rectangular and of a size corresponding to the preferred dimensions of the rectangular recess to receive it, said tongue will have sufficient strength to withstand all blows to which the furniture might be subjected and to maintain its 60 straight condition.

Means for preventing the longitudinal separation of the two members of the furniture, and for preventing the relative trans- 65 verse movement of said members, are pro-

vided. These means preferably comprise a shallow groove 18 extending longitudinally of the lower surface of tongue 12 and a similar longitudinal groove 18 on the under surface of the other tongue 13. These grooves extend parallel with the plane of separation 17 between the members of the furniture, and each groove is a little shorter than the length of the tongue, 12 or 13, in which it is formed. When each member is formed with a groove identically located, if the two members were viewed in the position of the single member shown in Fig. 3, with their tongues extending in the same direction, the positions of the grooves will be on the same side of the furniture when the two members are assembled; that is, the two grooves 18 will be at one side of the complete article of furniture, which could be used for the upper or the lower side. Preferably, the grooved portions of the furniture are on the bottom when the furniture is in use in the chase so as to preclude accumulation of ink, dirt, etc., in the grooves. The member 10 is provided at the inner end of its body portion, just before the tongue 12 thereof, with a small pin, stud or tongue 19, which is received in the groove 18 of the tongue 13. A correspondingly located pin 20 is provided on the body portion of the member 11, to enter the groove 18 in the tongue 12 of the member 10. In the preferred construction, these pins will be located at opposite sides of the plane of separation at 17. In any extended position of the members of the furniture, each of these 100 tongue-and-groove connections, 18, 19, and 18, 20, supplement the action of the other of them, in precluding lateral transverse separation of the two members away from the vertical plane of separation of the members at 17. Furthermore, the outer end 21 of each groove 18 forms a stop or abutment for the pin or tongue that is received in the corresponding groove, so that the two members may not be entirely separated longitudinally, although they can be extended for nearly the full length of the two members. 110

Each of the pins or studs 19, 20, is preferably in the form of a rivet, which is driven in place after the two members are assembled, and the head of each rivet is finished off flush with the surface through which it is inserted, and the whole surface is so polished as to hide the rivets. 115

It will be seen from the above description that the adjustable furniture is composed of two members which are inseparable from each other, and which cannot be separated transversely from each other; that is, each piece of furniture constitutes a unit, the parts of which will always be assembled, it simply being necessary to distend the two members in longitudinal alinement, or to push them together in longitudinal alinement. It is not necessary to use friction 120 125 130

for binding the parts of the furniture together, as they are always held together by suitable mechanical means so that they can be handled as a unit.

5 It is preferred to provide the upper and lower surfaces of the furniture, that is, each member 10, 11, with transverse ribs 22 spaced at suitable intervals apart, and with longitudinal edge ribs 23 connecting the transverse ribs. The flat upper and lower surfaces of the ribs lie in parallel planes and define the height of the furniture so that the same shall be less than type-high.

10 It is obvious that the invention is susceptible to more or less modification without departing from the scope and spirit of the invention as defined in the claims.

15 What I claim as new is:

1. Extension furniture for printers, constituting a complete article of manufacture less than type-high and having a width based on a unit of measurement used by printers, the furniture comprising two elongated members, which are longitudinally extensible the one on the other for substantially their full lengths, each of said members having a larger body portion, and said body portions being at the outer ends of the furniture, and co-acting means at the inner extremity of the smaller portion of one of said members and the inner extremity of the enlarged body portion of the other of said members, for precluding the longitudinal separation of said members when so extended, the restrictive action of said means being just sufficient to prevent such separation, and means at the meeting surfaces of said members for maintaining the lateral sides of the furniture always in one longitudinal, vertical, plane at any length of the furniture.

2. Extension furniture for printers, constituting a complete article of manufacture less than type-high and having a width based on a unit of measurement used by printers, the furniture comprising two similar members, extensible the one on the other along a vertical, longitudinal, plane of contact dividing said members into substantially equal parts, and duplicate parallel pin-and-groove connections between said members whereby they are transversely immovable with respect to each other and are longitudinally inseparable.

3. Extension furniture for printers, constituting a complete article of manufacture less than type-high and having a width based upon a unit of measurement used by printers, the furniture comprising two elongated members having a mutual sliding fit, and being substantially solid in cross section between the outer ends of the members when the members are entirely collapsed, each of said members having a larger body portion, and said body portions being at the outer

ends of the furniture, and means for holding the members together against transverse and longitudinal separation, all of the exterior lateral surfaces of said members being always in parallel planes at any length of the furniture.

4. Extension furniture for printers, constituting a complete article of manufacture less than type-high and having a width based upon a unit of measurement used by printers, the furniture being rectangular in cross section and comprising two elongated similar members having a mutual sliding fit, and being substantially solid in cross section between the outer ends of the members when the members are entirely collapsed, said members having larger, longitudinally recessed, body portions, at the outer ends of the furniture, and longitudinal tongues fitted in the recesses and which are rectangular in cross section so that the vertical, opposite, side walls of each tongue are of the same height and vertically continuous, the vertical height of all of said walls being approximately one-half of the vertical height of the entire furniture, and the adjacent walls of said tongues adapted to slide one on the other, and means for holding the members together against transverse and longitudinal separation, all of the exterior lateral surfaces of said members being always in parallel planes at any length of the furniture.

5. Extension furniture for printers, constituting a complete article of manufacture less than type-high and having a width based upon a unit of measurement used by printers, the furniture comprising two members slidably one on the other, within a given transverse dimension only, and means for preventing their transverse and longitudinal separation, consisting of duplicate tongue-and-groove connections therefor, one end of each groove having a stop-shoulder for the tongue, and the grooves being in the upper or lower walls of the members.

6. Extension furniture for printers, comprising two, elongated, similar members, which are longitudinally extensible the one on the other for substantially their full lengths, and means for permitting said members to be extended without separation, said means being duplicated along parallel lines to preclude relative transverse movement of the members.

7. Extension furniture for printers, comprising two, elongated, similar, members, which are longitudinally extensible the one on the other for substantially their full lengths, and a longitudinal tongue-and-groove connection for permitting said members to be extended without separation, said connection being duplicated along parallel lines to preclude relative transverse movement of the members.

8. Extension furniture for printers, comprising two, elongated, similar members, which are longitudinally extensible the one on the other for substantially their full lengths, and similar tongue-and-groove connections between said members, extending in parallelism on one side of the furniture, for precluding longitudinal separation of said members and their relative transverse movement.

9. Extension furniture for printers, comprising two similar members, fitted together to slide longitudinally of the furniture, each member including a larger body portion at one end and a longitudinal tongue at the other end, and each member having a longitudinal recess in which one of the tongues may slide, the inner vertical wall of the tongue of each member and the inner ver-

tical wall of the recess of the same member being alined, so that the inner walls of the two members extend in parallel vertical planes lengthwise of the furniture and are situated midway between the opposite, vertical, outside walls of the furniture, a longitudinal tongue-and-groove connection between said members, located to one side of said parallel vertical planes, and a similar longitudinal tongue-and-groove connection between said members, located at the other side of said parallel vertical planes, the two said connections extending parallel with said planes and being located at the upper or lower side of the furniture, whereby the longitudinal separation of said members and the relative transverse movement of said members are prevented.

HARRY H. HANCOCK.
